ABSTRACT

A chemical heater-cartridge for producing high amounts of heat without excessive pressure rises. A sealed, thin-walled, steel tube filled with solid lithium surrounding a core of Teflon powder forms the portable heater-cartridge. The exothermic reaction of this mixture, initiated by a pyrotechnic fuze, results in a high heat output and a reduction of pressure within the cartridge. This reduction of pressure permits the use of a small-mass tube which increases the rate of heat transfer. Sulfur hexafluoride vapor (SF₆) or Freon may be added under pressure to enhance the reaction rate. Alkali metals, other than lithium, and fluorocarbons, other than Teflon, may be used and are equivalent reactants.

1
CHEMICAL HEATER TUBE**BACKGROUND OF THE INVENTION**

1. Field of the Invention

The present invention relates generally to heating devices and more particularly to a portable heating cartridge employing a mixture of solid ingredients which react exothermically upon ignition. Because of their fast response, such heating cartridges make it feasible to boil water in water injection bottles and thus achieve the driving pressure necessary for the injection. The heaters can also be employed to melt ice and give pre-heat to a system to enhance starting capability.

2. Description of the Prior Art

In the field of one-shot heating devices chemicals which are initially contained in a closed container react to generate heat. Such heat sources have a wide variety of uses. However, most chemical reactions employed to produce high amounts of heat also produce excessive pressures within the container. The high pressures necessitate increases in container mass or strengthening of the container in various other ways to prevent its destruction. Such modifications cut down on the heat transfer capabilities of such a container and make it less efficient.

SUMMARY OF THE INVENTION

A pyrotechnic fuze is employed to ignite the reaction mixture within the heater-cartridge. The alkali metal and the fluorocarbon combine to release energy in an amount equal to that in the very highest of all known reactions based on either a weight or volume basis of the reactants. This tremendous heat is transferred through the steel tube to the surrounding environment. The addition of sulfur hexafluoride vapor or a Freon gas, i.e., fluorinated or chlorinated hydrocarbon gases under pressure has been found to enhance this reaction rate and reduce start-up time. Furthermore, by employing an excess of the alkali metals in this process, relative to stoichiometric proportions, the heat transfer and thus tube integrity may be controlled.

OBJECTS OF THE INVENTION

An object of the present invention is to produce a high heat output within a hermetically sealed container and yet not cause a pressure rise within that container.

A further object of the invention is to achieve a response time several orders of magnitude higher than an electrical heater of equivalent power rating.

Other objects, advantages, and novel features of the present invention will become apparent from the following detailed description of the invention when considered in conjunction with the accompanying drawings.

BRIEF DESCRIPTION OF THE DRAWINGS

FIG. 1 is a cross-sectional view of a heater-cartridge shown mounted in a container; and

FIG. 2 depicts a cross-sectional view taken along the line 2-2 of FIG. 1.

DESCRIPTION OF THE PREFERRED EMBODIMENTS

FIG. 1, which illustrates a preferred embodiment of the heater-cartridge, shows a tubular container 10 which may be formed of stainless steel. The container 10 may be hermetically sealed by a plug and pyrotech-

nic fuze indicated at 16. The container 10 holds a reactant charge including an alkali metal 12 surrounding a central fluorocarbon material 14. The alkali metal 12 may, for example, be lithium and the fluorocarbon Teflon. The chemical reaction for such a combination would be:

As can better be seen in FIG. 2 the lithium fills the container 10 with the exception of a center core which may be filled with tetrafluoroethylene powder. As shown in FIG. 1, the tubular container 10 may be employed to heat water in a water injection bottle to achieve the necessary driving pressure for injection.

To enhance the reaction rates, it is also desirable, but not necessary, to have a third reactant present. It has been found that sulfur hexafluoride vapor (SF_6) or Freon gas may be added under pressure to enhance the reaction rate. Such an addition adds to the energy liberated in the reaction.

It should be further noted that the charging pressure of the SF_6 or Freon gas is crucial. It has been found that 100 psig gives a start-up time of $\frac{1}{4}$ second as compared to 2-3 seconds for a 50 psig charge.

Except under unusual conditions, it is not feasible to install a stoichiometric mixture of the reactants in the tube. The adiabatic reaction temperature is of the order of $6,000^{\circ}\text{F}$, which will melt the containing structure unless the heat is dissipated from the outside of the tube at an exceedingly high rate. To solve this problem, the amount of fluorocarbon used will depend upon the heat transfer capability of the heater tube. The role played by the excess alkali metal in this process is not passive. Due to the very high thermal conductivity of liquid alkali metals, they serve as an excellent heat transfer medium between the reactive products and the container's metal wall. This fact also produces a heater with a very rapid response, several orders of magnitude higher than that in an electrical heater of equivalent range.

The tube is operated simply by detonating the fuze 16. A 1 inch diameter heating cartridge, 12 inches long with Teflon added to react with only one third of the lithium present, produces a heat equivalent in energy to that produced by a 600 watt electrical heater operating for a period of 20 minutes.

Obviously many modifications and variations of the present invention are possible in light of the above teachings. It is therefore to be understood that within the scope of the appended claims, the invention may be practiced otherwise than as specifically described.

What is claimed is:

1. A portable heater tube comprising:
a hermetically sealed container;
a reactant charge disposed within said container;
said reactant charge being composed of lithium, tetrafluoroethylene, and a third constituent chosen from the group consisting of sulfur hexafluoride and Freon gas; and
means connected to said container to initiate a chemical reaction in said reactant charge.

2. The portable heater tube of claim 1 wherein the lithium is present in excess amounts in proportion to a stoichiometric mixture.

3. The portable heater tube of claim 1, wherein the lithium substantially fills the container with the excep-

tion of a central core, said core being substantially filled with said tetrafluoroethylene.

4. The portable heater tube of claim 1 wherein the third constituent is sulfur hexafluoride at a charging pressure of at least 100 psig.

5. The portable heater tube of claim 1 wherein the third constituent is Freon gas at a charging pressure of at least 100 psig.

6. The portable heater tube of claim 5 wherein the lithium substantially fills the container with the exception of a central core, said core being substantially filled with said tetrafluoroethylene.

7. A portable heater tube comprising:

a hermetically sealed container; a reactant charge disposed within said container; said reactant charge being composed of lithium and tetrafluoroethylene, wherein the lithium fills the container with the exception of a central core, said core being filled with said tetrafluoroethylene; and means connected to said container to initiate a chemical reaction in said reactant charge.

8. The portable heater tube of claim 7 wherein the lithium is present in excess amounts in proportion to a stoichiometric mixture.
